US00D876431S

(12) **United States Design Patent** (10) Patent No.: **US D876,431 S**
(45) Date of Patent: ** *Feb. 25, 2020

(54) **ELECTRONIC DEVICE**

- (71) Applicant: **Elo Touch Solutions, Inc.**, Milpitas, CA (US)
- (72) Inventors: **Neeraj Pendse**, Palo Alto, CA (US); **Brian Perry**, San Jose, CA (US); **Jeffrey Haller**, Redwood City, CA (US)
- (73) Assignee: **Elo Touch Solutions, Inc.**, Milpitas, CA (US)
- (*) Notice: This patent is subject to a terminal disclaimer.
- (**) Term: **15 Years**
- (21) Appl. No.: **29/611,645**
- (22) Filed: **Jul. 24, 2017**

Related U.S. Application Data

- (63) Continuation of application No. 29/591,957, filed on Jan. 25, 2017, now Pat. No. Des. 794,630, which is a continuation of application No. 29/516,089, filed on Jan. 29, 2015, now Pat. No. Des. 778,279.

(57) **CLAIM**

The ornamental design for an electronic device, as shown and described.

DESCRIPTION

FIG. 1 is a bottom front perspective view of an electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the electronic device that form no part of the claimed design.

1 Claim, 5 Drawing Sheets
